UNITED STATES PATENT OFFICE.

WILLIAM A. JAMESON, OF NIAGARA FALLS, NEW YORK.

DESIGN FOR A SPOON.

SPECIFICATION forming part of Design No. 21,077, dated September 29, 1891.

Application filed August 17, 1891. Serial No. 402,905. Term of patent 3½ years.

To all whom it may concern:

Be it known that I, WILLIAM A. JAMESON, a citizen of the United States, residing at Niagara Falls, in the county of Niagara and State of New York, have invented and produced a new and original Design for Spoons, of which the following is a specification.

This design relates to the configuration of the bowl of a spoon, and is illustrated in the accompanying drawings, in which—

Figure 1 is a plan or face view of a spoon embodying my design, and Fig. 2 is a side elevation thereof.

The leading feature of my design consists in the raised ridges *a* in the concave face of the bowl and the grooves *b* in the convex back thereof, such ridges and grooves radiating in curved lines from the inner end of the bowl

to the edges thereof, and the two series of connected arcs or scallops *c*, which extend 20 from end to end of the bowl and diverge forwardly from its rear end to about its middle and converge forwardly from the middle of the bowl to its outer end, which latter terminates in a conoidal point or tip *d*, which is 25 bounded by the two outermost arcs or curves *c' c'*.

What I claim is—

The design for a spoon herein shown and described.

Witness my hand this 14th day of August, 30 1891.

WILLIAM A. JAMESON.
